UNITED STATES PATENT OFFICE

RODNEY V. NORTHEY, OF TORONTO, ONTARIO, CANADA

GIB AND WEDGE KEY FOR KEY BOLTS

Application filed November 4, 1927. Serial No. 231,109.

This invention relates to gib and wedge keys particularly adapted for use with a key bolt, that is, a bolt having its stem slotted for the passage of a wedge key which 5 takes the place of a nut. Such bolts are not ordinarily well adapted for use where much draft is required, as this necessitates either a very long key, or a key of steep pitch, and either alternative is objectionable. In my 10 prior Patent 1,563,518 I show a construction intended to partially overcome the objection referred to.

My chief object in the present invention is to devise a construction of gib with which 15 a shorter key may be employed.

It is also found that in some cases there is a tendency for the gib and key to move out of alignment as the key is driven, and a further object is to devise a construction in 20 which this tendency is to a large extent avoided.

I attain my object by forming the gib from a tapered metal bar and bending the bar at one or more points, and by longitudinally 25 grooving the contacting surface of either the gib or key and forming a rib on the contacting face of the other member.

The invention is hereinafter more specifically described and illustrated in the accompanying drawings in which

Fig. 1 is a side elevation of the improved gib and key used in connection with a key bolt, the latter being shown in section;

Fig. 2 a similar view showing the gib in another position;

Fig. 3 a side elevation of another form of gib;

Fig. 4 a side elevation of still another form of gib;

Fig. 5 a side elevation of the blank from which the gib is formed;

Fig. 6 a sectional view of the gib and key;

Fig. 7 a view similar to Fig. 6 showing a modified construction.

In the drawings like numerals of reference indicate corresponding parts in the different figures.

1 is a bolt formed with a slot 2, and 3 is a wedge key. The gib is formed from a 50 tapered piece of metal as shown in Fig. 5

and is preferably notched at 4 to facilitate bending.

In the form shown in Fig. 3, the gib is bent at one point to form in effect two connected gibs 5 and 6 lying at an angle to one another, while in the forms shown in Figs. 1, 2 and 6, the gib is bent at two points to form in effect three connected gibs 7, 8 and 9. In all forms the bar is preferably formed with a shoulder 10 at each end of the tapered side to prevent the gib slipping out while the key is being driven home. In the forms shown in Figs. 1 to 3 the straight sides of each portion of the gib lie at substantially an angle of 45° to one another, while in Fig. 4 the straight sides of the two outer portions lie at substantially a right angle to the straight side of the middle portion.

In Fig. 1 I illustrate in dotted lines the gib before bending, and it will be readily apparent that driving of the wedge key may be continued to a point considerably closer to the bolt than is possible with the straight gib, and therefore a shorter wedge key may be employed to secure the same amount of draft.

To prevent the gib and key working out of alignment during the driving operation, I form a longitudinal groove on the contacting face of one of the members, preferably the key thus forming a pair of spaced ribs, and a tongue on the contacting face of the gib. In Fig. 6 I show the groove and tongue as V-shaped and in Fig. 7 as rounded. The groove in each case is preferably deeper than the tongue so that the sides of the tongue engage the sides of the ribs before the tongue engages, the bottom of the groove. Hence, when driving the key home, there is a tendency for the tongue to cause the ribs to spread, thus effecting a greater frictional engagement between the parts which tends to prevent the accidental working loose of the key.

From the above description it will be seen that I have devised a construction of gib and key which will satisfactorily attain the objects of my invention as set out in the preamble of this specification.

What I claim is:

1. The combination with a slotted bolt of a

100

- wedge key and gib, said wedge key and gib having tongue and groove contacting surfaces tending to prevent transverse movement of the one relative to the other, the groove being deeper than the tongue whereby the 5 sides of the latter tend to spread the sides of the groove when the key is driven longitudinally of the gib.
2. A slotted bolt having a straight-sided wedge key extending through its slot in combination with a tapered gib, also extending through the slot, said gib bent intermediate its ends to form a pair of key engaging portions lying at an angle to one another. 10
3. A slotted bolt and a straight-sided wedge key extending through its slot in combination with a tapered gib also extending through the slot, said gib being bent at a plurality of points intermediate its ends to form a plurality of key contacting surfaces, any one of which may be brought into parallel contact with the wedge key and each lying at an angle to the adjacent surface. 15
4. A slotted bolt and a straight-sided wedge key extending through its slot in combination with a tapered gib, also extending through the slot, said gib being bent intermediate its ends to form a pair of key engaging portions lying at an angle to one another, 20 said gib and key having tongue and groove contacting surfaces tending to prevent transverse movement of the one relative to the other. 25
5. A slotted bolt and wedge key in combination with a tapered gib, said gib bent intermediate its ends to form a pair of key engaging portions lying at an angle to one another, said gib and key having tongue and groove contacting surfaces tending to prevent transverse movement of the one relative to the other, the groove being deeper than the tongue whereby the sides of the latter tend to spread the sides of the groove when the key is driven longitudinally of the gib. 30
6. The combination with a slotted bolt of a wedge key member and gib member each extending through the slot, one of said members having its surface which contacts with the other member grooved to form a pair of 35 spaced ribs extending longitudinally of the said member, said ribs being adapted to be spread apart by the other member when the members are being placed in wedged position. 40
7. The combination with a slotted bolt of a wedge key and gib each extending through the slot, the gib contacting surface of the wedge key being grooved to form a pair of spaced ribs extending longitudinally of the 45 wedge key, said ribs being adapted to be spread apart by the gib when the wedge key is being driven. 50
8. A slotted bolt having a straight-sided wedge key extending through its slot, in combination with a tapered gib, also extending 55
- through the slot, said gib bent intermediate its ends to form a plurality of key engaging portions lying at an angle to one another and having a bolt-engaging shoulder at each end thereof. 60
9. A tapered gib for use with a slotted bolt and a straight sided wedge key, said gib having a plurality of wedge portions arranged at an angle to one another, any of which may be brought into parallel contact with the wedge key, each wedge portion forming a bolt-engaging shoulder for the end of the adjacent wedge portion. 65
